HYDRAULIC MACHINE

Johannes Baumann, Heidenheim-on-the-Brenz,
Wurtemberg, Germany, assignor to J. M. Voith,
Heidenheim-on-the-Brenz, Germany, a copart-
nership composed of Walther Voith, Hermann
Voith, and Hanns Voith

Application January 9, 1934, Serial No. 705,855
In Germany January 10, 1933

3 Claims. (Cl. 253—141)

This invention relates to improvements in the construction of hydraulic machines, such for instance as pumps, hydraulic turbines, and the like, and more particularly to improvements in the construction of the impellers or runners of such machines.

An object of the invention is to provide an improved construction of the impeller or runner of a hydraulic machine of the Kaplan type having movable blades, so that machines of abnormal size can be manufactured and shipped to the place of installation.

Another object of the invention is to provide an improved construction of hydraulic machines in which the impeller or runner blades are first made in sections, to permit the parts to be transported to the site of installation, and then united into a homogeneous whole at the site of installation of the machine.

Another object of the invention is to provide an improved hydraulic machine of the character mentioned in which the impeller blades are detachably connected to their supporting trunnions.

Another object of the invention is to provide an improved hydraulic machine of the character mentioned, which is simple in construction, and reliable and exact in function under all conditions of service.

The invention also comprises certain new and useful improvements in the construction, arrangement and combination of the several parts of which it is composed as will be hereinafter fully described and claimed.

In the accompanying drawings:—

Figure 1 is a view partly in section of a Kaplan type of hydraulic turbine having impeller blades constructed according to the present invention;

Fig. 2 is an enlarged vertical section of the impeller, showing the construction of the parts within the hub thereof;

Fig. 3 is a section taken on the line 3—3 of Fig. 2, showing one of the impeller blades in plan;

Fig. 4 is a view similar to Fig. 3 showing another form of impeller blade;

Fig. 5 is a section taken on the line 5—5 of Fig. 4;

Fig. 6 is a view similar to Fig. 5 showing the two sections of the blade butted together preparatory to welding;

Fig. 7 is a plan of one of the sections of a blade;

Fig. 8 is a similar view of the other section of a blade.

Heretofore, in the construction of impellers or

runners of the Kaplan type of hydraulic machines, it has been customary to form the impeller blades in one piece. The blades are usually formed from cast iron, cast steel, cast bronze, or other suitable metal.

In the case of hydraulic machines having impellers of fairly large size, that is to say, machines having impellers with a maximum diameter exceeding approximately 8 feet, it has been difficult to transport the impellers from the factory to the site of installation, due to the fact that the impellers extended beyond the sides of the freight cars or other transportation vehicles. Therefore, due to the limitations of the sizes of transportation vehicles now in use, the maximum size of hydraulic machines which could be loaded on to the transportation vehicles at the place of manufacture and transported to the site of installation was limited.

In some cases it is of advantage to install a hydraulic machine having an impeller of extremely large size, but the size of such hydraulic machines has been limited to sizes which could be easily transported from the factory to the site of the installation.

According to the present invention the impellers can be constructed much larger than has heretofore been possible. This is accomplished by constructing the blades of the impellers in sections in such a manner as to materially reduce the sizes of the parts for shipping purposes. The sections of the impellers are so formed that they can be readily assembled together at the site of installation and then united into a homogeneous whole.

The preferred embodiment of the invention is shown in connection with the well known Kaplan type of hydraulic turbine.

Referring to the drawings and especially to Figs. 1 and 2, the turbine comprises a casing 11 which forms a peripheral water inlet in which are mounted an annular series of wicket gates or guide vanes 12, only a portion of which are shown. The lower portion 13 of the turbine casing forms an axially directed chamber in which the impeller 14 operates.

The hub of the impeller 14 is fixed to the lower end of a shaft 15 which is journaled in a suitable bearing 16 mounted in the turbine casing.

Any suitable type of setting may be used for the turbine installation, a concrete setting 17 being shown in the present instance. The portion of the setting below the turbine forms a draft tube 18 into which the water is discharged from the impeller.

As shown, the turbine is of the adjustable blade type, and a suitable number of blades 19 are rotatably supported in the hub of the impeller 14 and project radially therefrom. Each blade 19 has an entrance edge 20 and a discharge edge 21, both of which edges extend from the hub of the impeller 14 outwardly to the outer edge 22.

As shown in Figs. 2 and 3 the inner end of each blade 19 is provided with a trunnion 23 which is journalled in a bearing 24 supported in the hub.

The blade 19 is detachably secured to the trunnion 23 by means of bolts 25 which are passed through flanges 26 and 27 respectively formed on the blade and trunnion.

The flanges 26 and 27 constitute a collar 28 which is disposed in a suitable recess 29 formed in the hub.

Means are provided for simultaneously rotating all of the blades 19 and for maintaining them in equal angular relationship, such means comprising preferably an arm 30 rigidly fixed on the trunnion 23 of each blade and links 31 which pivotally connect the arms on the different blades to a cross head 32.

The cross head 32 is guided to reciprocate in a direction axially of the impeller by guide pins 33, which are mounted in the hub of the runner in the manner shown in Fig. 2.

As shown in Figs. 1 and 2 a cap 34 is bolted or otherwise removably secured to the lower end of the hub of the impeller 14.

The cross head 32 is bolted or otherwise fixed to the lower end of an operating rod 35 which extends upwardly through the hollow runner shaft 15 and is adapted to be operated by suitable means (not shown), such for instance as that shown in United States Patent 1,937,772, granted December 5, 1933, to Daniel J. McCormack for Hydraulic turbine.

In the form of the invention shown in Figs. 4 to 8 inclusive, each impeller blade 19 is composed of two sections or parts 37 and 38 which are joined together along a substantially radially disposed line 39 in the manner clearly shown in Fig. 4.

In forming the blade 19, the blade may be first formed from a single piece of metal having the general outline shown on Fig. 4. The blade can then be severed or cut along the line 39 (Fig. 4) so as to form the two sections 37 and 38.

Any suitable method or means may be employed to join the two sections of the blade together at the site of installation. In the instant case the sections of the blade are shown connected by welding 40 (Fig. 5).

In order to permit welding of the two sections of the blade together the adjoining edges 41 and 42 of the blade, sections 37 and 38 respectively, are bevelled, as indicated at 43 and 44 respectively in Figs. 6, 7 and 8. The welding metal is then formed in the V-shaped spaces 45 and 46 thus provided (Fig. 6), and in this way the parts will be united into a homogeneous whole in a well known manner.

By detachably connecting the blades to their respective trunnions in the above described manner the size and weight of the impeller will be materially reduced for shipping purposes, since the blades can be shipped separately from the hub of the impeller as will be understood. Furthermore, if the blades of the impeller are abnormally large they may be formed in the manner shown in Fig. 4 so that the two sections thereof can be

shipped separately to the site of installation. In this form of invention the several sections of the blades can be readily assembled at the site of installation of the turbine in the manner heretofore described. In this manner turbines of abnormal size and weight can be commercially produced since it is possible to form the largest part of the turbine in sections of a size convenient for transporting to the site of installation.

While two illustrative embodiments of the invention has been described in detail, it is not my intention to limit its scope to those embodiments or otherwise than by the terms of the appended claims.

Having thus described my invention what I claim is:

1. An impeller for hydraulic machines of extraordinary large size in which it is impracticable to ship the impeller as a whole from the place of manufacture to the site of installation, comprising a hollow hub, a plurality of blades, a trunnion journalled in the hub for each blade, means for detachably connecting the blades to said trunnions comprising, a flange formed on the outer end portion of each trunnion, a correspondingly formed flange on the inner portion of each blade and adapted to abut the flange of the trunnion, means for detachably securing the abutting flanges together, and recesses formed in the hub for said flanges. 30

2. An impeller for hydraulic machines of extraordinary large size in which it is impracticable to ship the impeller as a whole from the place of manufacture to the site of installation, comprising a hollow hub, a plurality of blades, a trunnion journalled in the hub for each blade, means for detachably connecting the blades to said trunnions comprising, a flange formed on the outer end portion of each trunnion, a correspondingly formed flange on the inner portion of each blade and adapted to abut the flange of the trunnion, means for detachably securing the abutting flanges together, and recesses formed in the hub for said flanges; and means within the hub and operatively connected with said trunnions for 40 simultaneously rotating the trunnions to change the angular positions of the blades. 45

3. An impeller for hydraulic machines of extraordinary large size in which it is impracticable to ship the impeller as a whole from the place of manufacture to the site of installation, comprising a hollow hub, a plurality of blades, a trunnion journalled in the hub for each blade, each of said blades comprising two sections divided along a line extending at an angle from the outer peripheral edge of the blade to the inner portion thereof, a flange formed on the outer end portion of each trunnion, a correspondingly formed flange on the inner portion of each blade, said blade flanges also being divided, so as to provide a blade structure 50 which is practicable to ship from the place of manufacture to the site of installation of the machine, means for joining the adjacent edges of the two sections of each blade so as to form a single blade of homogeneous construction having the desired configuration and a flanged portion adapted to abut the flange of each trunnion, recesses formed in the hub for the abutting flanges of each blade and trunnion, and means for 55 detachably securing the abutting flanges together, 60 said securing means also being disposed within said recesses in the hub. 65
